UNITED STATES PATENT OFFICE

2,578,471

ELECTRON TUBE FOR OPERATION WITH
SHORT WAVES

Pierre Grivet, Paris, France, assignor to Compagnie Generale de Telegraphie Sans Fil, a corporation of France

Application October 25, 1947, Serial No. 782,184
In France October 24, 1946Section 1, Public Law 690, August 8, 1946
Patent expires October 24, 1966

4 Claims. (Cl. 315—6)

1

It is well known that electronic tubes, whether they have three, four or five electrodes, become more and more defective when they work as amplifiers or oscillators, if the wave length of the electromagnetic oscillations involved becomes small and comes down to an order of value approaching one meter. The main difficulties which are met with in that field of application are the following:

(1) The space separating the anode from the cathode is too large, and the electrons take too long a time for going from the cathode to the anode; in other terms the transit time of the electrons becomes too important with reference to the oscillation period.

(2) The passage of the high speed electrons near the control electrode causes important interchanges of energy with the said electrode, resulting in considerable losses in its circuit.

(3) It is difficult to associate with the classical triodes such circuits as the ones which offer a symmetry of revolution, of the type of the rumbatrons or the resonant cavities for instance, which are the only efficient devices to be used in connection with the so-called decimeter waves.

My invention has for its object to partially solve those difficulties, by combining the two following means which are separately known:

(1) The use of volume resonators, or resonant cavities.

(2) A particular disposition of the electrodes within the tube, the said disposition substantially offering the three following characteristics:

(a) The cathode is made out of a relatively thin filament or of a plane mesh composed of some thin filaments.

(b) The anode and the control electrode are set on one side and the other of the plane of filament, or the multiple filaments. Within the tube thus composed, the filament, or filaments are thus disposed between the anode and the control electrode, instead of the control electrode between the cathode and the anode.

(c) As the electrons no longer run through the control electrode, the latter may now be made out of a non-perforated plate a condition which facilitates its cooling and improves its actual work.

A construction of that sort has already been proposed for some long wave applications, or for the amplification of direct currents.

My invention provides a construction permitting operation of tubes at very high frequencies. My construction possesses advantages that are derived from the elimination of the effects due

to the passage near the control electrode of the electrons intended for the anode. The tube of my invention is formed about a symmetry of revolution around an axis perpendicular to the plane of the active electrodes so as to facilitate the association with those electrodes of appropriate resonant cavities.

For a better understanding of my invention, reference will be made to the following description, which, together with the appended drawings, give non-limitative instances of embodiment, the particular features appearing from the said description, and the figures being, as should be understood, a part of the invention.

Figs. 1a and 1b represent in longitudinal and cross sections a type of triode for short waves to which the invention relates;

Fig. 2 represents one form of the emitting cathode which may be employed in the tubes of my invention;

Fig. 3 represents, viewed in cross section, the triode of Fig. 1 supplemented by an electrostatic screen;

Figs. 4a and 4b represent, in longitudinal and cross sectional views, respectively, a modified form of the screen shown in Fig. 3; and

Fig. 5 represents a completely assembled tube employing my invention.

Figs. 1a and 1b represent a triode built according to the invention. The anode is made out of a cylindrical copper rod 1, and the control electrode made out of another rod 2 having the same diameter and axis as 1. In the narrow space left between the ends of the said two rods I arrange the cathode, preferably composed of a filament 7, or of several elements soldered to two arc-shaped members 5 and 6, respectively connected to leading-in conductors, 3 and 4, sealed up in the glass 8 of the tube. The filament thus forms a flat sheet, extending over a width at least equal to the diameter of the rods 1 and 2. Such is the assembly shown in longitudinal section in Fig. 1a, and in Fig. 1b in a transverse section, made by a plane containing the filament sheet, thus perpendicular to the axis common to both the rods 1 and 2.

Experience shows that it is desirable to multiply the number of lead-in wires in order to facilitate the passage of the high frequency currents.

Fig. 2 shows an instance of a particularly efficient arrangement embodying my invention. As in Fig. 1b, Fig. 2 shows a section of the tube on a plane containing the so-called filament; the latter is composed of several strands which radiate from a central point 9 and ending in the

several lead-in seals shown at 10, 11, 12, 13, 14 and 15.

Such a construction lends itself particularly well to the heating of the filament, either by direct current or by alternating single phase current if the lead-in wires are parallel-connected by groups of three; it is also possible to heat up the filament by alternating hexaphase currents, since the six lead-in wires comprise a star connected system. At point 9 the filaments are all connected together, and they are flattened in such a way that the entire composite filament sheet offers the minimum thickness.

It is often desirable to reduce to the lowest possible value the capacity between the grid and the plate, and the presence of the filament may prove insufficient for that purpose. It is possible, in accordance with my invention, to complete the electrostatic action of the filament strands, by adding to it the effect of a metallic screen an instance of which is shown in Fig. 3. The said figure corresponds to Fig. 1b and bears the same reference numbers; but in addition to the components of the Fig. 1b can be seen, in Fig. 3, a screen made out of two semi-circles 16 and 17, respectively fixed up on the lead-in wires 3 and 4. The filament is disposed in an aperture cut out in the two semi-circular parts 16 and 17.

Figs. 4a and 4b show another embodiment of my invention, in which the screen 17 is made out of one single member and represent one of the poles of the sheet-filament. The whole of the tube is shown, in longitudinal section in Fig. 4a, and Fig. 4b represents a transverse section of the same taken on line 4-4 of Fig. 4a. It can be seen that the sheet-filament, comprising three elements for instance, has one of its extremities carried by a curved member 4 ending in three branches; each one of these elements is stretched between one terminal of a branch and three soldering points 21, 22 and 23 on the screen itself. Three elongated apertures 18, 19 and 20 are opened in the screen, so that the three elements, located along the axes of these respective apertures, are submitted to the influence of the field created by the anode 1 and the control electrode 2. Such a filamentary cathode is formed, in short, of three filaments connected in parallel; the source supplying its heating current is connected, on one side to the member 4, and on the other side to the screen itself.

Fig. 5 shows, in a longitudinal section, the association of a tube with two volume resonators or resonant cavities. The tube proper comprises the envelope 8, an anode 1, a control electrode 2, and a sheet-filament 7 having a given number of lead-in wires such as 3 and 4. The said lead-in wires are embedded in surface slots made out at the surface of an annular copper plate 28, and some of them are insulated from the plate by means of a thin sleeve, not shown, so that the heating of the filament may be effected by connecting to point 28 one of the poles of the source. At 25 and 26 can be seen the coaxial lines leading to the anode and control electrode circuits. The passage of the high frequency currents towards the cathode is insulated by the mica sheets 24, interposed between the flanges 27 of the concentric casing 29 and the ring 28. One at least of those coaxial lines 25 and 26 can slide with respect to the casing 29 containing the tube. It must be understood that the anode 1 and the control grid 2 slide at the same time

on their respective sleeves 30 and 31. Those adjustments can be effected with all the precision needed, by means of any accurate device, not shown in the figure. Two coupling means or loops 32 and 33 are provided, one formed to bring the incoming power to the control grid and the other formed for taking out the output power needed. By associating these coupling means with suitable circuits, the triode may be converted into an amplifier. The positive anode potential is applied at 34. The negative bias or the biasing resistance for the control electrode 2 can be connected at 35.

Under these conditions, and when the potentials are properly chosen, the tube works efficaciously with very short waves, as readily as would an ordinary triode with the conventional long waves.

When desiring a very high power efficiency, one can also, according to the invention, modify the triode shown in Fig. 5, and convert the same into a tetrode or a pentode. One or two supplementary grids are then inserted between the anode 1 and the filament 7; they are mounted on lead-in seals located in the median plane of the tube, as those connected to the filament strands, and they are introduced into the intervals of the latter. They can also be located in a plane parallel to the median plane above the filament. It is then possible, with an appropriate construction of the grids and of the filament, to obtain all the desired effects in the formation of the electron beams, in compliance with the usual technics governing the utilization of the tubes provided with several grids.

It should be understood that the above described devices are only given as mere instances, and non-limitatively. A number of detail modifications could be effected in these devices, without deviating thereby from the scope of the invention, substantially as described above.

What I claim is:

1. An electron tube comprising an anode and a control electrode, both of an elongated stem-like form and disposed on the same axis, and having their terminal faces opposed to each other, an emitting cathode of a planar form disposed perpendicularly to the axis and between the said electrode faces, an envelope surrounding said cathode and the parts of the anode and control electrode stems near said cathode, said envelope being open at both ends, and two terminal casings surrounding the central portion of the tube, and two enclosing end-casings connected with said terminal casings and comprising appended members adjustable along the anode and the control electrode, said end-casings forming two resonant cavities provided with means of taking out the output power on the anode side, and means for applying the incoming oscillations into the cavity on the control electrode side.

2. An electron tube as set forth in claim 1 in which the central portion and the end-casings are of cylindrical form.

3. A tube for operation on decimeter waves, comprising an anode and a control electrode, both in the form of solid stems, disposed along the same axis with their end faces facing each other, an emitting cathode of a flat form, disposed between the said faces and in a plane perpendicular to this axis, a vacuum-tight envelope of insulating material surrounding the said cathode and the ends of the stems of the other electrodes and forming a unit, a metal casing in the

form of a cylinder surrounding the said unit and having as its axis that of the said electrodes, this casing consisting of a fixed central portion supporting the said vacuum-tight envelope and open at its two ends and of two closed end portions in the form of end pots sliding frictionally on this central portion, and coupling means lodged in the said end pots.

4. A tube for operation on decimeter waves, comprising an anode and a control electrode, both in the form of solid cylindrical stems disposed along the same axis with their end faces facing each other, an emitting cathode forming a flat emitting surface, disposed between the said faces and in a plane perpendicular to this axis, a vacuum-tight envelope of insulating material surrounding the said cathode and the ends of the stems of the said electrodes, on the side of the cathode, said stems extending beyond the said envelope, a cylindrical metal collar surrounding the said envelope and supporting it and having as its axis that of the electrodes said cathode dividing said envelope into two parts, two closed metal casings in the form of pots of

a cylindrical form of revolution about the said axis and closing the said metal collar at its two ends to form two resonant cavities, their diameters being such that these casings can be frictionally displaced on the said collar, said casings presenting recessed appendices of a tubular form frictionally surrounding the external ends of the said stems of the electrodes, and coupling means lodged in the said cavities.
